CLAIM

The ornamental design for an upper portion of a dispenser, as shown and described.

DESCRIPTION

FIG. 1 is a perspective view of the upper portion of a dispenser of our design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines in the drawings showing the lower portion of the container, the thread detail and the inside of the bottom surface of the container illustrate portions of the design that forms no part of the claim.
